UNITED STATES PATENT OFFICE.

FRANKLIN DICKEY, OF INDIANAPOLIS, INDIANA.

AIR-HEATER FOR INTERNAL-COMBUSTION ENGINES.

1,310,412.

Specification of Letters Patent. Patented July 22, 1919.

Application filed March 12, 1917. Serial No. 154,352.

To all whom it may concern:

Be it known that I, FRANKLIN DICKEY, a citizen of the United States, residing at Indianapolis, in the county of Marion and State of Indiana, have invented a new and useful Improvement in Air-Heaters for Internal-Combustion Engines, of which the following is a specification.

My invention relates to certain accessories for internal combustion engines, and more particularly to a device for supplying heated air thereto. The invention will be fully understood from the following detailed description of one specific embodiment thereof, taken in connection with the accompanying drawings, in which—

Figure 1 is a side elevation of a common form of the internal combustion engine used in automobiles, the dash-board of the automobile being shown in section for the purpose of illustrating the control mechanism for the air heater. Fig. 2 is a bottom plan view of the heater *per se*. Fig. 3 is an enlarged sectional view substantially on a line 3 of Fig. 1, and Fig. 4 is an enlarged sectional view on a line 4 of Fig. 1.

Referring more particularly to the drawings, the numeral 10 designates a four-cylinder internal combustion engine of a common form and provided with an inlet manifold 11 and an exhaust manifold 12, which are arranged in generally parallel relationship, the exhaust manifold lying above the inlet manifold. For the purpose of supplying heated air to the inlet manifold 11, I provide a heater, generally designated by the numeral 13, this heater being preferably constructed of cast-metal and being of U-shape in cross-section and provided with flanges 14 at its open edge, these flanges being curved to the radius of the exhaust manifold 12, on which the heater is designed to rest. The ends of the heater casting 13 are closed by integral webs and air is permitted to enter the interior of the casting through a plurality of grooves or notches 15 formed in the bearing face of one of the flanges 14 adjacent the ends of the heater. The casting is secured in place on the top surface of the manifold 12 by some suitable means, such as a clamp 16, illustrated in Fig. 3, being secured by one of the engine bolts 17.

For feeding the heated air from the heater 13 to the inlet manifold 11 there is provided a conduit 18 connected with the inlet mani-

fold by an elbow 19 and with the heater by an elbow 20, the latter elbow carrying a plug valve 21 which may conveniently be operated by a rod 22 passing through the dash-board 23 of the automobile, and having an operating handle on its inner end. In the particular construction of the invention illustrated it is not intended that the plug valve 21 should be used for graduating or adjusting the amount of heated air to be supplied to the inlet manifold, the valve being intended solely as a cut-off and not as a regulator. The function of regulation is accomplished in the construction shown by the provision of an aperture 24, of predetermined size, forming a connection between the interior of the heater 13 and the elbow 20. In order to provide sufficient metal for the adequate fastening of the threaded end of the elbow 20 and for the regulating perforation 24, the heater casting may have an integral lug 25 extending inwardly at the point of attachment of the elbow.

By reason of the fact that my air heater is formed with relatively heavy metal walls, curved to fit the wall of the exhaust pipe 12 and have contact therewith over a considerable area, the heat of the exhaust manifold is readily conducted to the heater casting and transferred by the latter to the air passing therethrough. Since the wall of the exhaust manifold itself forms one of the confining surfaces for the air in its passage through the heater, the effectiveness of the latter is further increased.

The atmospheric air heated as above described is supplied to the intake manifold 11 through the regulating aperture 24 and cut-off valve 21, and serves to dilute the explosive mixture within the intake manifold, increasing the density of the charge at the same time that the dilution is effected, and by such increase in density raising the compression of the engine and increasing the thermal efficiency thereof. The effective heating of the air by the heater 13 is of benefit in that a better vaporization of the fuel charge is effected, and also in that the pre-heating of this portion of the air raises the temperature of the entire incoming charge, and by proportionately raising the maximum temperature in the cylinder, increases the thermal efficiency. For the reasons stated, I find that my auxiliary air inlet device will effect a considerable saving in fuel.

While I have shown and described in considerable detail one specific embodiment of my invention, it will be understood that this is illustrative only, and for the purpose of 5 making the invention more clear, and that I do not regard the invention as limited to these details nor to any of them, except in so far as such limitations are included within the terms of the accompanying claims, in 10 which it is my intention to claim all novelty inherent in my invention as broadly as is permissible in view of the prior art.

What I claim as new, and desire to secure by Letters Patent, is:

- 15 1. The combination with the exhaust pipe of an internal combustion engine, of an air heater comprising a U-shaped hollow metallic member closed at its top and ends and provided with a flanged open bottom adapted to seat on said exhaust pipe in heat conducting relation therewith, one of said flanges being provided with air-admitting
- 20 2. The combination with the exhaust pipe of an internal combustion engine, of an air heater comprising a U-shaped hollow metallic member closed at its top and ends and provided with a flanged open bottom adapted to seat on said exhaust pipe in heat conducting relation therewith, one of said flanges being provided with air-admitting

openings, said air heater being also provided with a relatively small air-discharging opening adjacent its top, and a pipe connecting said air-discharge opening with the intake pipe of the engine.

2. The combination with the exhaust pipe of an internal combustion engine, of an air heater comprising a U-shaped hollow metallic member closed at its top and ends and provided with a flanged open bottom adapted to seat on said exhaust pipe in heat conducting relation therewith, one of said flanges being provided with air-admitting 35 openings, said air heater being also provided with a relatively small air-discharging opening adjacent its top, a pipe connecting said air-discharge with the intake pipe of the engine, and means in said pipe for closing the same to cut off the current of air therethrough.

FRANKLIN DICKEY.
